Application April 4, 1947, Serial No. 739,505

4 Claims. (Cl. 29—155.55)

1

The present invention relates in general to improvements in the art of attaching a succession of similar elements in predetermined order to a series of elongated members, and relates more specifically to an improved method of and apparatus for electrically connecting successive groups of terminals to successive spaced portions of a plurality of insulated wires or conductors.

It has heretofore been proposed as shown and described in my copending application Serial No. 469,526, filed December 19, 1942, now abandoned, to construct terminal banks for automatic telephone systems, by longitudinally advancing a series of insulated wires radially toward a common axis, by positioning successive arcuate groups of radially disposed terminals adjacent to the wires of the advancing series near said axis, by crimping corresponding terminals of the successive groups to the same wires through the insulation of the latter so as to produce a chain of electrically interconnected terminal groups, and by finally stacking the terminal groups into arcuate banks having predetermined terminals thereof connected by predetermined wires, without resorting to soldered attachments. While this crimping of the terminals through the insulation, did in fact greatly facilitate assembly of the terminal banks by eliminating the laborious and costly prior method of soldering each terminal to a selected wire, it is possible that the presence of the insulation at the attaching zones might occasionally prevent perfect electrical contact between the insulation piercing prongs of a terminal and the adjacent wire especially when the attachments are being produced by machinery and in rapid succession. In order to avoid this possibility of production of imperfect electrical connections while still retaining the advantages of the crimping method of attachment and bank assembly, I have discovered that more perfect and dependable unions may be secured with the same general procedure and machinery as that revealed in my prior application and without interfering with speed of production, by positively removing the wire insulation at the successive attaching zones before the terminals are crimped to the wires at these zones.

It is therefore a primary object of my present invention to provide an improved method of and apparatus for expediting attachment of successive similar elements such as groups of terminals, to a plurality of elongated members such as insulated electric current conducting wires, in a manner whereby perfect electrical connections

2

are insured while the interconnected elements and members may still be readily assembled into final stacks such as efficient telephone switch banks.

5 Another object of this invention is to provide a method of directly connecting arcuate groups of terminals to longitudinally advancing insulated wires, by removing the insulation from successive local zones or portions of the wires, and by 10 crimping selected terminals of the successive groups to the bared areas of predetermined wires of the advancing lot.

A further object of the present invention is to 15 provide reliable and automatically functioning apparatus for carrying on commercial exploitation of my improved method of terminal group and conducting wire assembly, by effectively removing the insulation from the local portions of the continuous wires and by subsequently firmly 20 crimping the selected terminals to the bared zones.

Still another object of my invention is to provide an improved system for mechanically assembling a succession of similar elements such 25 as groups of multiple switch terminals and a plurality of elongated members such as continuous insulated copper wires, at high speed and in a most accurate and dependable manner, so that perfect electrical contact between the terminals 30 and the wires is always assured without resorting to fusion of metals such as soldering.

An additional object of the invention is to provide a new mode of most effectively electrically connecting selected terminals of successive 35 unitary cards or groups, to bared local zones of insulated longitudinally advancing wires, while twisting adjacent pairs of the progressing wires about each other on opposite sides of each zone of attachment of a terminal.

40 These and other objects and advantages of the present invention will be apparent from the following detailed description.

A clear conception of the several steps involved 45 in my improved method, and of the construction and operation of typical apparatus for effecting automatic commercial exploitation thereof, may be had by referring to the drawings accompanying and forming a part of this specification in which like reference characters designate the same or similar parts in the various views.

50 Fig. 1 is a somewhat diagrammatic section through one of my improved insulated wire clamping and insulation removing or stripping units for holding, stripping, and transferring an adjacent pair of wires;

Fig. 2 is a similar section through the clamping and insulation removing unit, showing the same in action to strip the insulation from local areas or portions of the held wires;

Fig. 3 is a transverse section through the clamping and insulation removing unit of Figs. 1 and 2 showing the complementary pair of wires in position, the section having been taken along the line 3—3 of Fig. 1;

Fig. 4 is an end view of one of the wire spacers and stripping elements, removed from the clamping and insulation stripping unit;

Fig. 5 is a diagram of a typical terminal and wire assembling machine showing the movable terminal crimping die elevated, the wire transporting slide moved away from the crimping zone and lowered to bring the wire feeding and insulation stripping fingers thereof into insulation shearing action adjoining each other as in Fig. 1, while the wire twisting rotor is inactive;

Fig. 6 is another diagram of the machine, showing the wire feeding and insulation stripping fingers of the transporting slide, moved apart as in Fig. 2 to strip the insulation off of or away from adjacent local areas of the wires, and also showing the wire twisting rotor in action to twist the pair of wires about each other adjacent to the stripped zone while the wires are being transported longitudinally;

Fig. 7 is a similar diagram of the machine, showing the stripping fingers spread apart as in Fig. 6, and the wire transporting slide moved forwardly to position the bared portions of the wires close to the final crimping zone, while the wire twisting rotor is again inactive;

Fig. 8 is still another diagram of the machine, showing the stripped portions of the wires lowered adjacent to the terminals of an arcuate group, and the movable crimping dies operating to effect attachment of the terminals to the bared wires, while the wire twisting rotor is still inactive;

Fig. 9 is an additional diagram of the machine, showing the upper crimping die and the wire feeding fingers and transporting slide elevated away from the crimping zone, but with the arcuate terminal group still held at the crimping zone and the wire twisting rotor active to twist the adjacent pairs of wires;

Fig. 10 is a further similar diagram of the machine, showing the crimping dies fully separated and the transporting slide and feeding fingers being moved rearwardly, while the adjacent pairs of wires are still being twisted about each other;

Fig. 11 is a final similar diagram of the machine, showing the crimping dies fully separated and the feeding and stripping fingers about to be brought together and lowered for coaction with a succeeding portion of the wires, while the wire twisting rotor is again inactive; and

Fig. 12 is an enlarged diagrammatic plan view of a fragment of the partially completed chain of wires and terminal groups produced by the machine while carrying on my present improved method.

Although the invention has been shown and described herein as being advantageously applicable for effecting attachment of corresponding terminals of successive flat arcuate groups to the same insulated wires of a series while the latter are being advanced longitudinally in a horizontal direction, it is not my desire or intention to thereby unnecessarily restrict the utility of the improved method and apparatus.

In my prior application, Serial No. 469,526, filed

December 19, 1942, I have revealed an improved method of electrically connecting or attaching the corresponding terminals of successive similar arcuate cards or groups, to the same longitudinally advancing insulated wires of a series, and of twisting adjacent pairs of the wires about each other on opposite sides of the several points of attachment, by providing each individual terminal with integral metallic points which were driven through the insulation and embedded within the stranded copper wires by cooperating dies, without removing the insulation from the wires at the attaching areas. The present improvement contemplates the provision of a similar method, but the improved method differs from the prior one by virtue of the fact that I now positively remove the insulation from each area of attachment of the terminals and wrap the metal of each terminal directly about the bared portion of the adjacent wire, thereby insuring more perfect electrical contact without however resorting to soldering or the like. The improved method may be carried on commercially with apparatus quite similar to that shown and described in my said prior application, by merely providing additional mechanism for removing the insulation from the several wires at the proper localities, and the major portion of this apparatus will therefore be only diagrammatically disclosed herein, while the modification necessary for the present improvement will be more specifically shown and described.

Referring to the drawings, the apparatus shown is adapted to automatically produce a continuous chain of wire and arcuate terminal group assemblies a partially completed fragment of which is shown in Fig. 12, and as specifically illustrated, each arcuate card 14 consists of a group of twenty sheet metal terminals 15 radiating from a common center, to each of which an insulated wire 16 is electrically connected by crimping the metal of the terminal 15 about a bared portion of the adjacent wire 16. The wires 16 may be either stranded or solid, and the completed chain may be severed into sections of suitable lengths each containing a number of cards 14, and these cards may finally be assembled in stacks or banks for use in connection with automatic telephone systems, in a well known manner.

The apparatus for producing the improved chains of Fig. 12, comprises in general a frame forming a crimping or card attaching zone 17 having lower and upper relatively movable dies 18, 19 respectively cooperable therein to simultaneously crimp all of the terminals 15 of each successive card 14 to the successive locally bared portions 20 of the several wires 16 presented to the zone 17; a revolvable card supply table 21; a card transfer and holding pad 22 cooperable therewith for properly positioning the successive cards 14 within the zone 17; a plurality of horizontally reciprocable radially directed main slides 24 each having thereon a set of wire gripping and insulation removing fingers 25, 26 adapted to cooperate with a pair of the insulated wires 16 to transport these wires longitudinally toward the assembly zone 17; a multiplicity of wire guiding and twisting rotors 27 each housed within an independent casing 28 and each adapted to conduct a pair of the insulated wires 16 toward the corresponding set of stripping and transfer fingers 25, 26; a number of wire supply reels each having a wire guide 29 cooperable therewith to conduct the individual wires 16 in pairs toward one of the rotors 27; a final conveyor 30 for trans-

ferring the continuous chain assembly away from the uniting zone 17; and suitable driving mechanism for periodically actuating the various machine elements to automatically exploit the improved method.

The lower and upper crimping dies 18, 19 are formed and operable to firmly wrap the metal of the terminals 15 about the bared portions 20 of the adjacent wires 16, and there is a cooperating set of these dies 18, 19 provided for each of the twenty terminals of the successive cards or groups 14. The card supply table 21 is intermittently revolvable to present the successive cards 14 deposited in spaced relation upon the periphery thereof, to the positioning pad 22, and this pad is movable fore and aft upon links 32 to assist in the transfer of the new arcuate cards 14 with their radiating terminals in position for distortion by the dies 18, 19 within the crimping zone 17, and to also hold the cards while the dies are being withdrawn. The reciprocable wire feeding slides 24 besides being movable toward and away from the assembly zone 17, are also movable vertically at certain intervals, and the upper dies 18 are movable through openings or gaps between the spread fingers 25, 26 of the corresponding slides 24 whenever a crimping operation is being effected.

The slides 24 and the dies 18, 19 may all be mounted for movement in the common sturdy frame, and each of the main slides 24 carries an auxiliary slide 34. The front wire gripping and insulation removing finger 25 of each slide assembly is carried directly by the auxiliary slide 34, whereas the rear finger 26 is carried directly by the main slide 24, and the two slides of each assembly are simultaneously movable toward and away from the zone 17 but they are also relatively movable to separate or spread the fingers 25, 26 as illustrated in Figs. 1 and 2. Each finger 25, 26 is provided at its lower end with two laterally spaced notches 35 each of which is bounded by a cutting or knife edge as shown in Figs. 1, 2 and 3, and these knife edges are adapted to cut through the top and sides of the insulation 36 of the wires 16 presented thereto, while the fingers 25, 26 are in contact with each other as in Fig. 1. When the fingers 25, 26 are subsequently spread apart by relative movement of the slides 24, 34 as in Fig. 2, the knife edges of the notches 35 remove or strip the insulation 36 to produce the bared wire portions 20, but the notches 35 continue to snugly embrace and to firmly hold the wires 16 after such stripping has been effected.

In order to properly position the wires 16 for entry thereof into the notches 35 and to prevent the wires from dropping or excessively sagging away from the descending fingers 25, 26, a pair of spreaders 37 such as shown in Fig. 4, are provided at each of the slide assemblages. Each cooperating set or pair of these spreaders 37 is swingably suspended by means of pivot pins 38, from a vertically movable supporting block 39, and the spreaders 37 of each pair are constantly urged toward each other by leaf springs 40 secured to the intervening block 39 and coacting with the adjacent spreaders 37. Each spreader 37 is provided with an upwardly directed central point 42 having projections 43 on the opposite sides thereof, and the top of each of these projections 43 is provided with a cutting or knife edge 44 which is cooperable with the knife edges of the adjacent or corresponding finger 25, 26 to cut and strip the insulation 36 from the bottoms

of successive portions 20 of the wires 16, as clearly shown in Figs. 1 to 4 inclusive in order to insure clean cutting of the insulation entirely around each wire. The points 42 of the spreaders 37 are always spaced apart sufficiently to permit lowering of the transfer fingers 25, 26 therebetween, when these fingers are in engagement with each other; and as these fingers are moved away from each other they move the spreaders apart. After these fingers have been spread apart to produce a bared wire portion 20 on a pair of complementary wires 16, and the spreaders 37 have been lowered away from the wires, the leaf springs 40 become quickly effective to return the released spreaders toward each other, to the position indicated in Fig. 1.

The wire guiding and twisting rotors 27 which are journaled for periodic rotation within the fixed casings 28, are located between the wire guides 29 and the wire spreaders 37, and each of these rotors 27 coacts with a complementary pair of the wires 16 to guide this pair of wires for longitudinal advancement radially of the crimping zone 17, and to also periodically twist the wires 16 about each other on the opposite sides of each successive pair of bared wire portions 20. Each of these rotors 27 is provided with a pair of laterally separable wire guiding fingers which are normally held together by clamps 46, but which are adapted to separate and to twist the wires 16 about each other during various definite periods of operation of the machine. The machine is also provided with other structures for insuring proper guiding of the wires and for releasing the cards 14 from the dies after each crimping operation, and the mechanism for driving the various movable parts in properly timed relation, is shown and described in detail in my copending application above referred to.

As previously indicated, the mechanism just described is adapted to automatically exploit my new method, and in order to clearly indicate the manner in which this is done, one cycle of operations will be described, it being understood however that successive similar cycles are normally repeated in rapid succession. When the mechanism is disposed as shown in Fig. 5, all of the composite slides 24 have been moved away from the crimping zone 17 as far as possible, and lowered to cause the fingers 25, 26 thereof to cut through the insulation 36 of the wires 16 as in Fig. 1, while the wires 16 are resting on the knife edges 44 of the spreaders 37. The rotors 27 are stationary at that time so that no twisting of wires is being effected, and the wire guiding fingers of the rotors 27 are clamped together by the clamps 46, although the complementary wires of each pair will have been temporarily twisted adjacent to their guide wheels 29 during a previous operation of these rotors. The dies 18, 19 are separated to the fullest extent, and while the parts are in this position, the slides 24, 34 of each slide assembly will be moved relative to each other so as to separate the fingers 25, 26 thereof and to produce a bared portion 20 on each wire 16, as in Fig. 2.

Upon completion of this insulation stripping operation, the spreaders 37 will be lowered so as to cause the spread fingers 25, 26 to clear the tips 42 of these spreaders, whereupon the slides with the wires 16 suspended therefrom, will be moved toward the crimping zone 17, as depicted in Fig. 6. The dies 18, 19 will remain separated, but the pad 22 will have been withdrawn to permit the table 21 to place a new card 14 into

position for elevation into the zone 17 by the lower die 18; and as the slides 24, 34 proceed toward the zone 17, they pull fresh wire stock from the corresponding supply spools past the wire guide 29 and through the rotors 27. The clamps 46 are also released and the rotors 27 are revolving, thereby permanently twisting the pairs of wires 16 about each other between each set of transfer fingers 25, 26 and the corresponding rotor 27 but unwinding the temporary twists previously applied to wires between each rotor 27 and its wire guide wheels 29.

This longitudinal transportation of the wires 16 toward the terminal attaching zone 17 and the final twisting of each pair of wires about each other, continues until the slides 24, 34 have reached the position illustrated in Fig. 7, whereupon the twisting action of the rotors 27 ceases, and the bared portion 20 closely approach final crimping position. The pad 22 then moves rearwardly to hold the new cards 14 in proper position while the lower dies 18 move upwardly and the upper dies 19 move downwardly.

While the twisting rotors 27 are still at rest, the slides 24, 34 finally stop in the crimping zone 17 and the lower dies 18 simultaneously elevate the new card 14 with its terminals 15 directly beneath the bared wire portions 20, while the upper dies 19 descend through the spaces between the fingers 25, 26 of the slides, and cooperate with each other to firmly clamp the terminals 15 about the adjacent stripped portions 20 of the wires 16, as shown in Fig. 8. During this final crimping operation, the pad 22 will be moved forwardly to clear the lower die 18 and its card elevating structure, and the slides 24, 34 are so formed as not to interfere with the downward crimping motion of the upper die 19.

Upon completion of each terminal attaching or crimping operation, the upper dies 19 and the slides 24, 34 coating therewith, are elevated in unison, but the lower dies 18 remain elevated momentarily while the pad 22 is moved beneath the newly attached card 14, and the rotors 27 are revolved so as to again twist the complementary wires 16 on the opposite sides of each rotor, as depicted in Fig. 9. This twisting operation does not unwind the previous permanent twists 48 applied to the wires, but in fact starts a new twist 49 in each pair of wires 16 remote from the prior twist 48, see Fig. 12.

The wire twisting operation continues while the upper dies 19 are being withdrawn from between the transfer fingers 25, 26, and the lower dies 18 are descending, as illustrated in Fig. 10, and during this withdrawal of the lower dies, the pad 22 remains effective to hold the terminal card 14 which has just been attached to the wires 16, within the crimping zone 17. The upward movement of the slides 24, 34 is arrested when the fingers 25, 26 thereof have cleared the wires 16 and the attached card 14, whereupon the slides are ready for their return stroke.

When the elevated slides 24, 34 and have been moved rearwardly to a position directly above the spreaders 37, the twisting operation of the rotors 27 ceases, and the spreaders are raised as shown in Figure 11 to cause the points 42 thereof to pass between the adjacent pairs of twisted wires 16 and to be clamped against the sides of the points 42, thus assuming the positions shown in Fig. 1. The slides 24, 34 are subsequently lowered and the fingers 25, 26 are simultaneously brought together for proper entry between the corresponding sets of spreaders 37, thus placing

the apparatus in condition for a repetition of the cycle.

From the foregoing description of the step-by-step operation of the machine, it will be noted that the mechanism is in fact adapted to automatically and accurately carry on the improved method by removing the insulation from successive equally spaced portions 29 of the wires 16 and by crimping the terminals of the successive cards 14 directly to the bare wires 16 in predetermined order. Because of the fact that the terminals need not necessarily pierce the wires, the improved method and apparatus may be utilized to effect attachment of terminals to either solid or stranded wires. The improved insulation removing mechanism functions to positively cut and strip the insulation from each area or wire portion 20 without danger of damaging the wires 16, and the final attachment is effected without resorting to soldering or the like. While the improved method and apparatus are advantageously applicable for the production of card and wire chains for telephone systems, this method and mechanism may also be utilized for other similar purposes, and the improvement obviously insures production of perfect electrical connections between the terminals 15 and wires 16 while the machine is operating at high speed. While the twisting of complementary pairs of wires about each other on opposite sides of each point of terminal attachment, is not essential, it is advantageous, and such twisting may be just as readily effected with the improved method as was possible with the method covered by my prior application herein referred to.

It should be understood that it is not desired to limit this invention to the exact steps of the method or to the precise details of construction of the apparatus, herein shown and described, for various modifications within the scope of the appended claims may occur to persons skilled in the art; and it is also contemplated that specific descriptive terms used herein be given the broadest possible interpretation consistent with the disclosure.

I claim:

1. The method of stripping and of attaching terminals to successive bared portions of a continuous insulation covered wire, which comprises, causing an insulation covered medial portion of the continuous wire to rest upon a lower pair of adjoining cutting edges and moving an upper pair of adjoining cutting edges downwardly toward the lower edges in the plane of adjointment to completely sever the insulation entirely around the wire at said plane, separating the two adjoining sets of cooperating cutting edges to push the severed ends of the insulation along the wire away from said plane, dropping the lower cutting edges away from the wire and moving the upper separated cutting edges while still in engagement with the severed separated ends of the insulation in the direction of extent of the wire to shift the bared wire portion to another locality and to simultaneously longitudinally advance the continuous wire, and clamping a terminal directly about the bared wire portion at said other locality.

2. The method of stripping and of attaching terminals to successive bared portions of a continuous insulation covered wire, which comprises, causing an insulation covered medial portion of the continuous wire to rest upon a lower pair of adjoining cutting edges and moving an upper

pair of adjoining cutting edges downwardly toward the lower edges in the plane of adjoinment to completely sever the insulation entirely around the wire at said plane, separating the two adjoining sets of cooperating cutting edges to push the severed ends of the insulation along the wire away from the wire, dropping the lower cutting edge away from the wire and moving the upper separated cutting edges while still in engagement with the severed separated ends of the insulation in the direction of extent of the wire to shift the bared wire portion to another locality and to simultaneously longitudinally advance the continuous wire, clamping a terminal directly about the bared wire portion at said other locality, and repeating said stripping and terminal attaching operations at successive equally spaced localities along the length of the continuous wire.

3. In a mechanism for stripping and attaching terminals to successive bared portions of a continuous insulation covered wire, a pair of adjoining lower cutting edges, means for positioning an insulation covered medial portion of a continuous wire upon said lower cutting edges, a pair of adjoining upper cutting edges movable toward said lower cutting edges in the plane of adjoinment thereof to completely sever the insulation entirely around the wire at said plane, means for separating the said lower and upper adjoining cutting edges while completely encircling the wire to push the severed ends of the insulation along the wire away from said plane, means for thereafter removing the lower cutting edges from the wire, means for subsequently moving the upper separated cutting edges while still in engagement with the severed separated insulation ends in the direction of extent of the wire to shift the bared wire portion to another locality and to simultaneously advance the continuous wire longitudinally, and means for clamping a terminal directly about the bared wire portion at said other locality.

4. In a mechanism for stripping and attaching terminals to successive bared portions of a continuous insulation covered wire, a pair of adjoining lower cutting edges, means for positioning an insulation covered medial portion of a continuous wire upon said lower cutting edges, a pair of adjoining upper cutting edges movable toward said lower cutting edges in the plane of adjoinment thereof to completely sever the insulation entirely around the wire at said plane, means for separating the said lower and upper adjoining cutting edges while completely encircling the wire to push the severed ends of the insulation along the wire away from said plane, means for thereafter removing the lower cutting edges from the wire, means for subsequently moving the upper separated cutting edges while still in engagement with the severed separated insulation ends in the direction of extent of the wire to shift the bared wire portion to another locality and to simultaneously advance the continuous wire longitudinally, means for clamping a terminal directly about the bared wire portion at said other locality, and means for returning said lower and upper cutting edges to insulation severing and stripping positions.
